Primary Examiner — Mark Goodwin(74) *Attorney, Agent, or Firm* — Fish & Richardson P.C.(57) **CLAIM**

The ornamental design for a feeder for a road paving machine, as shown and described.

DESCRIPTION

FIG. 1 is a perspective view of a feeder for a road paving machine showing my new design.

FIG. 2 is a left side elevation view thereof.

FIG. 3 is a right side elevation view thereof.

FIG. 4 is a front elevation view thereof.

FIG. 5 is a rear elevation view thereof.

FIG. 6 is a top plan view thereof; and,

FIG. 7 is a left rear perspective view thereof.

The bottom view being devoid of surface ornamentation forms no part of the claimed design.
